SEPARABLE MACHINE OR EQUIPMENT HANDLE

Filed Aug. 16, 1950

A diagram of a cylindrical component. It features a central longitudinal slot. At each end of the slot, there is a circular feature. The feature on the left is labeled 38 and the feature on the right is labeled 37. The entire assembly is labeled with the number 27 at the top right.

SEPARABLE MACHINE OR EQUIPMENT
HANDLE

Claude Vincent O'Maley, Richmond, Ind., assignor to The Moto-Mower Company, Detroit, Mich., a corporation of Michigan

Application August 16, 1950, Serial No. 179,826

3 Claims. (Cl. 16—111)

1

This invention relates to machine and equipment handles and, in particular, to demountable handles which are separable for shipment or storage.

One object of this invention is to provide a machine or equipment handle of a parallel frame construction having upper and lower frame portions which are capable of being separated into their individual components or into upper and lower units in order to adapt them for more convenient shipment or storage.

Another object is to provide a machine or equipment handle which is composed of parts adapted to fit into the carton or other container in which the machine itself is shipped, thereby having all parts of the machine in a single container without danger of losing or separating the various parts.

Another object is to provide a machine or equipment handle of a parallel frame construction wherein the upper and lower portions are separate units, each of which is of bent construction so that in assembly the upper bent portions form handle bars and the lower bent portions a yoke for attachment to the machine or equipment with which the handle is used.

In the drawings:

Figure 1 is a front elevation of a machine or equipment handle, according to one form of the invention;

Figure 2 is a side elevation of the handle shown in Figure 1; and

Figure 3 is a horizontal section taken along the line 3—3 in Figure 1.

Hitherto, in lawnmowers or other machines or equipment guided or propelled by a handle, it has been customary to ship the handle separately from the machine because the great length of the handle does not readily adapt itself to shipment in the same container as the remainder of the machine. This policy, however, has frequently resulted in handles being lost or mislaid so that when the machine is to be assembled, it lacks the proper handle. Furthermore, the ordinary lawnmower is a very unwieldy piece of equipment when it is desired to transport it by automobile, particularly in the trunk of an automobile. The present invention provides a demountable handle which can be separated either into upper and lower units or completely knocked down into its individual components, in either case being compact enough to be packed in the same carton or container as the remainder of the machine.

Referring to the drawings in detail, Figure 1 shows a machine or equipment handle, generally designated 10, consisting generally of an upper or handle unit 11 and a lower or yoke unit 12 secured to one another by a coupling unit or structure 13. The upper and lower units 11 and

2

12 are united to one another end to end so that the handle 10 may be separated approximately into halves. The upper and lower units 11 and 12 are made of such length as to fit conveniently within the carton in which the lawnmower cutting unit is packed, thereby placing all parts of the machine in a single container.

The upper unit or handle unit 11 consists of a pair of upper frame members 14 having shaft or lower portions 15 connected to handle bar portions 16 by bent portions 17. The upper frame members 14 are preferably of tubular construction and on their upper ends are preferably provided with hand grips 18 of rubber or other suitable material. The portions 15 and 16 are preferably bent approximately at right angles to one another for convenience of use. The frame members 14 are spaced apart from one another by a spacer, generally designated 19 consisting of a block or bar 20 bored as at 21 to receive a tie bolt or other fastener 22 which also passes through holes 23 in the shaft portions 15 just below the bent portions 17. The lower ends 24 of the shaft portions 15 abut the upper ends 25 of the yoke members 26 in end to end relationship.

The lower or yoke unit 12 consists of two of these yoke members 26 having substantially parallel upper portions 27, outwardly bent upper intermediate portions 28, inwardly bent lower intermediate portions 29, and parallel lower portions 30 terminating in flattened end portions 31 provided with holes 32 for the attachment of the machine or other equipment. The yoke members 26 are thus bent in opposite directions to one another and are also preferably of tubular construction.

The upper and lower units 11 and 12 are spaced apart from one another and also connected to one another by the coupling unit or structure 13 which is in the form of a block 33 having grooved opposite edges 34 (Figure 3) configured to fit the shaft portions 15 of the upper frame members 14 and also to fit the upper straight portions 27 of the yoke members 26. The block 33 is provided with spaced drilled holes 34 (Figure 3) aligned with similar holes 36 and 37 in the frame members 14 and yoke members 26 respectively. There are preferably two holes 35 in the upper half of the block 33 and two holes 35 in the lower half of the block 33, so that the block 33 will be approximately equally distributed between the handle unit 11 and the yoke unit 12. In other words, the line of junction or parting line between the lower ends 24 of the frame members 14 and the upper ends 25 of the yoke members 26 will lie approximately halfway along the vertical extent of the block 33. Bolts or other fasteners 38 are inserted through the holes 36 or 37 and 35 to clamp the frame members 14 and

yoke members 26 firmly and rigidly to the block 33, the block 33 and the fasteners 38 collectively constituting the connecting device 13.

Assuming that the handle 10 is assembled in the manner shown in the drawings, to disassemble it into halves, the operator removes the upper pair of bolts or other fasteners 38, thereby freeing the upper unit 11 from the lower unit 12, and leaving the block 33 in place between the yoke members 26 of the lower unit 12. If the carton 10 is large enough, the upper and lower units 11 and 12, thus separated, may be packed in it. If more compactness is desired or is necessary, however, all of the bolts 38 are removed, together with the bolt 22, causing the blocks 20 and 33 to become separated from the frame members 14 and yoke members 26 respectively. The bolts 22 and 38 may then be replaced in their respective blocks 20 and 33, so as not to be lost. The handle, when thus disassembled to its maximum extent, then consists of two frame members 14 equipped with hand grips 18, two yoke members 26 and two blocks 20 and 33 carrying their respective bolts 22 and 38. This makes a total of six pieces to be packed in the carton or other container for the machine.

To reassemble the machine handle 10, the foregoing procedure is reversed. The blocks 20 and 33 are placed in position with the frame members 14 engaging their opposite sides or ends, as the case may be, and when the respective bolt holes are lined up, the bolts 22 and 38 are inserted and their nuts applied and tightened. The lower or yoke members 26 are then brought into engagement with the lower side portions of the block 33 with their ends 25 approximately in abutment with the ends 24 of the frame members 14, whereupon the holes 37 and 35 will be in alignment. The lower pair of bolts 38 may then be inserted and their nuts applied and tightened, forming the component parts into a substantially unitary and rigid handle which is both strong and free from weaving as well as light and attractive in appearance. Moreover, the upper and lower blocks 20 and 33 furnish a convenient means of lifting the entire machine when it is desired to pick it up to place it in a truck or upon an elevated surface.

What I claim is:

1. A machine or equipment handle comprising an upper handle unit having a pair of approximately parallel elongated frame members spaced laterally apart from one another and having oppositely and outwardly bent upper ends collectively forming a handle bar; a lower handle unit having a pair of spaced yoke members with approximately parallel upper portions also spaced laterally apart from one another substantially the same distance as the spacing of said frame members and placed substantially end to end with said frame members, said yoke members having outwardly bent lower portions with lower ends configured for attachment to the machine; and a coupling structure having a width substantially equal to the lateral spacing of said frame members and said yoke member upper portions disposed between said upper portion of said frame members and between said yoke members, said coupling structure having a length relatively short in proportion to its width and overlapping said frame members and yoke members only in the immediate vicinity of their adjoining ends whereby said coupling structure also serves as a lower hand grip for handling the machine or equipment to which it is attached.

2. A machine or equipment handle comprising an upper handle unit having a pair of approximately parallel elongated frame members spaced laterally apart from one another and having oppositely and outwardly bent upper ends collectively forming a handle bar and having a laterally-elongated spacing member forming an upper hand grip disposed therebetween; a lower handle unit having a pair of spaced yoke members with approximately parallel upper portions also spaced laterally apart from one another substantially the same distance as the spacing of said frame members and placed substantially end to end with said frame members, said yoke members having outwardly bent lower portions with lower ends configured for attachment to the machine; and a coupling structure having a width substantially equal to the lateral spacing of said frame members and said yoke member upper portions disposed between said upper portion of said frame members and between said yoke members, said coupling structure having a length relatively short in proportion to its width and overlapping said frame members and yoke members only in the immediate vicinity of their adjoining ends whereby said coupling structure also serves as a lower hand grip for handling the machine or equipment to which it is attached.

3. A machine or equipment handle comprising an upper handle unit having a pair of approximately parallel elongated frame members spaced laterally apart from one another and having oppositely and outwardly bent upper ends collectively forming a handle bar; a lower handle unit having a pair of spaced yoke members with approximately parallel upper portions also spaced laterally apart from one another substantially the same distance as the spacing of said frame members and placed substantially end to end with said frame members, said yoke members having outwardly bent lower portions with lower ends configured for attachment to the machine; a coupling structure having a width substantially equal to the lateral spacing of said frame members and said yoke member upper portions disposed between said upper portion of said frame members and between said yoke members, said coupling structure having a length relatively short in proportion to its width and overlapping said frame members and yoke members only in the immediate vicinity of their adjoining ends whereby said coupling structure also serves as a lower hand grip for handling the machine or equipment to which it is attached, the lower end portions of said frame members and the upper end portions of said yoke members being each provided with a plurality of spaced transverse holes and said coupling structure being provided with transverse holes aligned with said previously-mentioned holes; and fasteners mounted in said holes and securing said frame members and said upper portions of said yoke members respectively to said connecting structure.
